Inventor

UNITED STATES PATENT OFFICE.

LEWIS M. KELLOGG, OF LOS ANGELES, CALIFORNIA.

DRUM PRESS FOR FABRICATED MATERIALS.

Application filed January 2, 1923. Serial No. 610,396.

To all whom it may concern:

Be it known that I, LEWIS M. KELLOGG, a citizen of the United States, residing at Los Angeles, in the county of Los Angeles and 5 State of California, have invented new and useful Improvements in Drum Presses for Fabricated Materials, of which the following is a specification.

My invention relates to improvements in 10 presses adapted to compress firmly fabricated materials which have been put together with glue or other binder and which require time and pressure for the glue or binder to set, the objects being to provide a press having 15 capacity to continually receive and compress the fabricated material as it is discharged from a loom or other manufacturing machine; another object being to provide a press having a compressing means which 20 glue or binder will not stick to and which can be easily cleaned; still another object being to provide a rotating press having a compressing medium which clamps the fabricated material between perfectly flat and un- 25 yielding surfaces; the device being adapted, more particularly, to press thin ply wood or a wood fabric woven from thin ribbons of wood and glued in the lap of the warp and weft, with waterproof glue, which requires 30 immediate and continued pressure.

With reference to the drawings—

Fig. 1 is a side elevation of the entire device including a loom.

Fig. 2 is a top view of the device as shown 35 in elevation in Fig. 1, with the loom omitted.

The present invention comprises a compression drum 1, having a shaft 2 rotatably mounted in bearings 3, 3 which are secured to a concrete foundation 4, and a reel drum 5 having a shaft 6 mounted in bearings 7, 7 secured to a concrete foundation 8.

The drum 1 is adapted to be rotated by a worm gear 9 rotatably mounted upon the shaft 2, there being a clutch 10 slidably mounted upon the shaft 2 adapted to engage the hub of the gear 9 and through which the shaft may be turned.

The worm gear 9 is operated by a worm 11 carried upon a shaft 12 which is mounted 50 in bearings 13, 13 and which has a band pulley 14. Four posts, 15, 15 are set upon the

foundation 4 and support a frame 16, 16, which carries a beam 17 and a pressure roller 18. The roller 18 bears against the drum on one side and the beam 17 carries a plurality 55 of shoes 19, which bear against the drum on the opposite side, there being a retractile spring 20 disposed between each shoe and the beam. Upper and lower arms 21, 21 extend from the shoes 19 and rest slidably upon the beam 17. The roller 18 is carried in slidably mounted bearings, in the frame 16, which are moved towards the drum by retractile springs as shown.

The drum 1 is adapted to be wound with 60 spring steel or brass bands 22, the ends of which are fixed to the drum, the bands passing under a rubbing block 23 and over a guide roller 24. The guide roller 24 is provided with thin metal discs 25 between each 65 band which keep the bands separated and in proper alignment.

The reel drum 5 is composed of a plurality 70 of narrow band wheels each of which is rotatably carried upon the shaft 6. Arms 26, 26 are positively mounted upon the shaft 6 and carry a bar 27 between the spokes of the band wheels forming the drum 5. Between the bar 27 and a spoke of each band wheel is a retractile spring 28 so that a 80 movement of the band wheels is caused by, or resisted by the springs 28 and bar 27.

Upon the shaft 6 two friction brake wheels 29, 29 are positively mounted. Brake levers 30, 30 and 31, 31 are pivoted at their bottom 85 ends in the foundation 8, two of which bear oppositely upon each of the brake wheels. Each pair of brake levers is pulled together at the top by bolts 32 and 32, there being tension spring 33 and 33 upon the bolts as 90 shown.

The drum 5 is rotated by a worm 41 carried upon a shaft 42 having a band pulley 43, the shaft being mounted in bearings 44, 44. The worm 41 meshes with a worm wheel 45 which is rotatably carried by the shaft 6, there being a clutch 46 adapted to slide upon the shaft 6 to engage the hub of the worm gear and thereby cause a rotation of the 95 shaft.

The other ends of the bands 22 are fixed 100 one to each of the band wheels of the drum

5 and it is to be understood that there is provided a sufficient length of the bands 22 to wind around the drum 1 any desired number of times, all of which may be carried on the drum 5.

The bands used may be of what is known to trade as ribbon steel and ground to an even thickness and width. By brazing end on end the bands may be made several hundred 10 feet long and should be of exactly equal length. In assembling the device one end of each band is fixed one to each of the band wheels of the drum 5 and nearly the entire length of the bands is then wound thereupon. The other ends are then carried under 15 the rubbing block 23 and over the guide roller 24 and fixed to the drum 1 in proper alignment.

A loom is positioned between the two 20 drums as shown, the bands 22 passing under the loom. Briefly the loom comprises a frame 34 at one end of which is carried warp reels 35, in the center holding frame guides 36 and a shuttle 37. The warp is indicated by 25 lines 38 and a weft 39 is shown in the shuttle, the weave being indicated by the numeral 40 discharging into the windings of the compression drum.

In the operation of the device the brake 30 levers 30, 30, and 31, 31 bear firmly enough to properly resist the rotation of the band wheels of the drum 5 and maintain the steel bands at a proper tension. The clutch 42 is released from the worm wheel 41 and the 35 clutch 10 is engaged with the worm wheel 9 of the drum 1.

A power belt over the pulley 14 will then 40 rotate the drum 1 to wind up the bands from off the drum 5. The fabricated material 40 is then fed to the drum 1 between the layers of the winding bands, the drum 1 being rotated just fast enough to take up the material as it is discharged from the loom.

The shoes 19 and roller 18 which bear upon 45 the drum 1 act to rub down the bands so that they present an even face alignment and aid in compressing the fabric and, while the bands are being rewound upon the reel drum, to hold a tension on them so that the re-winding will proceed evenly.

After the required length of the fabric is wound upon the compression drum the fabric is then cut off and an extra turn or two of the bands is wound upon the drum 55 to insure the last of the fabric being properly compressed. The drum is then left to stand the required length of time for the glue to set when it is unwound, the bands upon the reel drum and the sheet of compressed fabric upon a separate reel to dry or otherwise disposed of. This last operation 60 of unwinding the compression drum is effected by disengaging the clutch 10 of the drum 1 and engaging the clutch 46 of the drum 5 when, with a power belt over the

pulley 43, the reel drum is wound up against the resistance of the roller and shoes on the drum 1. For this operation the pressure of the levers 30, 30 and 31, 31 on the brake wheels 29, 29 may be relieved.

70

The rubbing member pressing against the drum 1 acts to clean the bands on one side, in winding and rewinding, of any foreign particle which might come off the fabric and the rubbing block 23 may perform the same office on the other side of the bands. The bands may be greased slightly to prevent glue and the like from sticking to them.

75

The shoes 19 of the drum 1 may be replaced with a roller should the rubbing element drag too strongly on the bands in the compression of some fabrics.

80

A single wide band is impractical to use in place of the plurality of narrow bands for it is pointed out that the press must be made 85 wide enough to receive fabric of a width of from four to ten feet and such a wide single sheet of metal would be hard to make up without buckling and developing uneven pressure in winding, hence for such a purpose the narrow bands must be adapted.

90

It is to be understood that the width and number of the bands used forms no part of my present invention and that many changes might be made in the invention as shown 95 without departing from the spirit thereof as claimed.

I claim:

1. In a drum press in combination with a wood weaving loom, the loom, a compression drum rotatably mounted in alignment with the loom and adapted to be driven at a proper speed to receive a woven fabric issuing from the loom, a reel drum positioned in alignment with the compression drum, a plurality of flexible bands having one end of each fixed to the reel drum and disposed side by side without a space between to cause the fabrics to become marked by noncompression, means for keeping the bands in proper alignment and the other ends to the compression drum, means for winding the bands upon the compression drum under tension with the fabric issuing from the loom and means for unwinding the bands from the compression drum upon the reel drum.

110

2. In a drum press in combination with a wood weaving loom, the loom, a compression drum rotatably mounted in alignment with the loom and adapted to wind up a fabric discharged therefrom, a reel drum, rotatably mounted in alignment with the compression drum, a plurality of flexible bands having one end of each fixed to the compression drum and the other ends fixed to the reel drum, means for winding the bands upon the compression drum under tension with the fabric, means for unwinding the bands from the compression drum

115

120

125

130

- upon the reel drum, thereby unwinding the compressed fabric and means for cleaning the bands of glue and other matter while being wound from one drum onto the other.
5. 3. In a drum press in combination with a wood weaving loom, the loom, a compression drum rotatably mounted in alignment with the loom and adapted to wind up a fabric discharged therefrom, a reel drum 70 rotatably mounted in alignment with the compression drum, a plurality of flexible bands having one end of each band fixed to the compression drum and the other ends fixed to the reel drum, means for winding 75 the bands upon the compression drum under tension with the fabric discharged from the loom, means for maintaining the winding of the bands upon the compression drum at an even face alignment and means for 80 unwinding the bands from the compression drum upon the reel drum whereby the compressed fabric is released.
4. In combination in a drum press, a compression drum rotatably mounted, means for 85 rotating the compression drum, a reel drum rotatably mounted, means for rotating the reel drum, a flexible band having one end fixed to the reel drum and the other end fixed to the compression drum and adapted 90 to be wound from off one drum onto the other, means for cleaning the band on both sides thereof in passing from one drum onto the other, and means for resisting the movement of the band as it is being wound 95 upon the compression drum.
5. In a drum press in combination, a compression drum rotatably mounted, a rotatably mounted reel drum positioned in alignment with the compression drum, a plurality 100 of flexible bands having one end of each fixed to the compression drum and the other ends fixed to the reel drum, means for winding the bands from one drum onto the other and means operating upon the compression 105 drum adapted to cause the winding of each band to proceed at the same circumference and present an even face alignment across the drum.
6. In combination in a drum press, a compression drum rotatably mounted, a rotatably mounted reel drum positioned in alignment 110 with the compression drum, a plurality of flexible bands having one end of each fixed to the compression drum and the opposite ends fixed to the reel drum, means for winding the bands from one drum onto the other, and means adapted to maintain 115 separately a tension on each individual band while the bands are being wound from one drum onto the other.
7. In a drum press in combination a compression drum rotatably mounted, means for 120 rotating the compression drum, a reel drum rotatably mounted, means for rotating the reel drum, a flexible band having one end 125 fixed to the compression drum and the other end fixed to the reel drum and adapted to be wound from one drum onto the other, means for maintaining a tension on the band while being wound upon the compression 130 drum, means for maintaining a tension on the band while it is being wound upon the reel and means for cleaning the band on both sides as it is wound from one drum onto the other.
8. In a drum press in combination, a compression drum rotatably mounted, a reel drum comprising a plurality of narrow band wheels rotatably carried upon a common shaft, means for rotating the shaft, a plurality of narrow flexible bands having one end of each fixed to the compression drum and the other ends fixed one to each of the narrow band wheels, means positively 135 mounted upon the shaft of the reel drum adapted to cause a rotation of the band wheels, and means for compensating for differences in the length of the narrow bands adapted to maintain an even tension on each band separately while the bands are being wound and rewound.
9. In a drum press in combination, a compression drum rotatably mounted, a rotatably mounted reel drum positioned in alignment with the compression drum, a plurality of flexible bands having one end of each fixed to the compression drum and the other ends fixed to the reel drum, means for winding the bands upon the compression 140 drum under tension, means for rewinding the bands upon the reel drum and a guide means mounted to operate upon the bands between the two drums adapted to maintain all the bands in proper alignment while being wound and rewound.
10. In combination in a drum press, a compression drum rotatably mounted, means for rotating the compression drum, a reel drum comprising a plurality of narrow band wheels rotatably mounted upon a common shaft, bearings for the shaft, arms fixed to the shaft, one on either side of the plurality of band wheels a bar extending from one arm through all the band wheels to the other arm, retractile springs, one disposed between the bar and a spoke of each of the band wheels, means for rotating the shaft, a plurality of narrow flexible bands having one end of each band fixed to the compression drum and the other end of each band fixed one to each of the band wheels, the bands being adapted to be wound from one drum onto the other, and means for maintaining a tension on the bands while being wound upon the compression drum.
11. In combination in a drum press a compression drum rotatably mounted, means for rotating the compression drum, a reel drum comprising a plurality of narrow band wheels rotatably mounted, means for rotat-

ing the reel drum, a plurality of narrow flexible bands having one end of each band fixed to the compression drum and the other end of each band fixed one to each of the 5 band wheels, the bands being adapted to be wound from one drum upon the other, means for maintaining a tension on the bands

while being wound from one drum upon the other, and means for cleaning the bands while being wound from one drum upon the 10 other.

In testimony whereof, I have signed my name to this specification.

LEWIS M. KELLOGG.
